UNITED STATES PATENT OFFICE.

JULES AYER, OF LONDON, ENGLAND.

HEADLIGHTS OF VEHICLES.

Application filed October 25, 1923. Serial No. 670,735.

To all whom it may concern:

Be it known that I, JULES AYER, a subject of the King of Great Britain, residing at London, England, have invented certain new and useful Improvements in and Relating to the Headlights of Vehicles, of which the following is a specification.

The present invention relates to headlights for motor cars and similar lamps which have a parabolic reflector and an incandescent lamp, the reflector being divided so as to have a stationary forward portion and a movable pivoted rear portion.

This kind of lamp is designed to give the usual beam ahead for ordinary driving, but on the approach of an oncoming vehicle, or for other purposes, the usual beam is changed to a non-dazzling beam by altering the focus of the source of light in the head-lamp.

An object of the present invention is to provide an improved construction of lamp of this kind which possesses manufacturing facilities and in use is very efficient in exhibiting a non-dazzling beam while at the same time giving sufficient soft light to illuminate the road for safe driving and passing.

The accompanying drawings illustrate a lamp according to the present invention, Fig. 1 being a sectional elevation, and Fig. 2 a sectional plan view thereof.

Referring to the drawings a lamp *a* is shewn having an adjustable bulb *b* and a rear reflector part *g* divided such as by way of example by a straight cut or division *h* from the forward part of the paraboloidal reflector *i* and the bulb *b* and the rear reflector part *g* are mounted to turn together on a horizontal medial axis *j* located behind the source of light to put the source of light out of focus with respect to the forward part of the paraboloidal reflector *i* so as to spread the rays reflected therefrom and dip the beam projected from the rear part of the reflector, thereby modifying a dazzling beam to a non-dazzling beam and realizing at the same time the effect of a dipping headlight without its disadvantages. The rear reflector part may be actuated about the axis *j* which is remote from the split or division in the reflector by rod, wire, or other appropriate connection such as *k* related to a control within easy reach of the driver.

The rear reflector part *g* as shown may have appropriate spring provision for re-

turning this to normal position, for example, mouse-trap springs *l*, *l* may be mounted on the axis *j*, each spring having one end anchored to or restrained by a fixed part of the lamp such as one of the pair of arms *m*, *m* made fast with and extending rearwardly from the non-tilting forward part of the reflector *i* to carry the tilting axis *j*, and having the other end anchored or restrained by the wall of the rear reflector part *g*.

By way of example the axis *j* is shewn as formed of opposite cylindrical projections *n*, *n* from the lamp socket holder *o* of the rear reflector part *g*, and corresponding opposite cylindrical bearings *p*, *p*, on the arms *m*, *m*.

The non-tilting forward part *i* is provided with a stop *q* on its upper side to arrest and definitely position the rear reflector part *g* for normal functioning of the lamp.

The lamp socket holder *o* and the lamp socket *r* are shewn in Fig. 3 as adapted for screw connection allowing the necessary adjustment for focussing, and the adjustment when made may be appropriately locked such as by the set screw *s*.

t is the usual glass fronted hinged door of the lamp, and *u* the socket mounts.

A test carried out for the applicant showed that a lamp constructed substantially as described normally throws a beam effective for fast driving, but when the bulb and the rear part of the reflector is tilted downwards, part of the beam is thrown at an acute angle onto the road immediately in front of the car and another part of the beam is spread and diffused, and there is ample light at the sides and nearer portion of the roadway to enable the car to proceed at a good speed, while at the same time to anyone approaching the lamp, this appears to be hopelessly out of focus but producing an even light in front without any blinding or irritating glare. A test was made driving a car with the headlamps out towards a car fitted with the aforesaid lamp but controlled as described to throw a non-dazzling beam, and it was particularly noticeable with what great ease the last mentioned car could be passed, as its lamp gave sufficient soft light to show the approaching driver the road.

Such a headlight is particularly serviceable in fog or mist as the dipped beam is of

great assistance for picking up a curb, hedge, etc.

What I claim is:—

1. A vehicle headlight of the kind described comprising in combination a divided reflector having a stationary front portion and a movable rear portion, a pivot mount on which said rear portion tilts downwardly, said pivot mount being located at the back of said movable rear portion of the reflector and remote from the forward portion thereof, mechanical means for downwardly tilting the rear portion of the reflector to cast the rays downwards and shield the upper surface of the stationary reflector portion from the source of light, means for returning the movable rear portion of the reflector to normal position, and a stop to arrest and definitely position the rear reflector part for normal functioning of the lamp.
2. A vehicle headlight of the kind de-

scribed comprising in combination a divided reflector having a stationary front portion and a movable rear portion, a pivot mount on which said rear portion tilts downwardly, 25 said pivot mount being located at the back of said movable rear portion of the reflector and remote from the forward portion thereof, a joint guide support for the rear reflector part supported from the forward part of the reflector, mechanical means for downwardly tilting the rear portion of the reflector to cast the rays downwards and shield the upper surface of the stationary reflector portion from the 30 source of light, and means for returning the movable rear portion of the reflector to normal position.

In testimony whereof, I affix my signature.

JULES AYER.
